WATCH STRAP SPRING BAR

Abraham I. Coleman, Baltimore, Md.

Application August 16, 1950, Serial No. 179,830

2 Claims. (Cl. 24—265)

1

This invention relates to the class of watch making and more particularly to means for securing straps to wrist watches.

An object of this invention is to provide a watch strap spring bar that is readily adjustable for use with different size wrist watches.

Another object of this invention resides in the provision of means for lockingly adjusting and limiting the size of the watch strap spring bars used in securing the straps to wrist watches so as to prevent non-intentional disengagement of the watch strap spring bars from the wrist watch, the same means being adaptable for enabling the removal of the strap when such is so desired by intentional movement of the split collars forming said means so as to enable a decrease in size of the spring bars.

Perhaps the most important feature of the present invention resides in the provision of the means for adjustably limiting the size of the watch strap spring bars. This means may comprise suitable split collars which are frictionally adjustably secured on the watch strap spring bars or may consist of the threaded surfaces for so adjusting the various elements as to size.

Still further objects of the invention reside in the provision of watch strap spring bars that are strong, durable, highly efficient in operation, simple in construction and manufacture, capable of being readily emplaced on various sizes of watches and capable of being constructed with male or female engaging surfaces so as to be adaptable for connection to various types of watches, and which watch strap spring bars will be relatively inexpensive to manufacture.

These, together with the various ancillary objects of the invention which will become apparent as the following description proceeds, are attained by these watch strap spring bars, preferred embodiments of which have been illustrated in the accompanying drawings, by way of example only, wherein:

Figure 1 is a longitudinal sectional view of a first embodiment of the present invention;

Figure 2 is a plan view of the embodiment of the invention shown in Figure 1;

Figure 3 is a plan view of another form of the invention;

Figure 4 is a longitudinal sectional view showing the details of the construction of the embodiment of the invention as shown in Figure 3;

Figure 5 is a plan view of a further form of the invention;

Figure 6 is a longitudinal sectional view showing the construction of the various details of the third embodiment as shown in Figure 5;

Figure 7 is a plan view of a fourth embodiment of the present invention;

Figure 8 is a longitudinal sectional view of the embodiment as shown in Figure 7;

Figure 9 is a plan view of yet another embodiment of the invention;

2

Figure 10 is a longitudinal sectional view of the embodiment of the invention shown in Figure 9; and

Figure 11 is a sectional view as taken along line II—II in Figure 3 and showing the construction of the split collar.

With continuing reference to the accompanying drawings, wherein like reference numerals designate similar parts throughout the various views, and with particular reference to Figures 1 and 2, the reference numeral 10 generally designates an outer tubular member which is provided with an end wall 12 having an aperture therethrough in which the projecting end 14 of a stud having a head 16 extends. The tubular member 10 is provided with a crimp 18 providing a reduced sleeve and to provide means for preventing disengagement of said outer tubular member 10 from the inner tubular member 20 which is slidably adjustably emplaced within the confines of the outer tubular member 10. The tubular member 20 is first inserted within the tubular member 10 before the crimp 18 is formed and the inner tubular member 20 is provided at its innermost end with an expanded portion 22 of greater diameter for engagement with the crimped portion 18 so as to provide engaging means.

The inner cylindrical member 20 is provided with a crimped edge 24 and has a portion of greater diameter 26 formed about the crimped edge 24. The crimped edge 24 retains the collar 28 of the stud 30 within the confines of the inner cylindrical member 20 and prevents disengagement of the stud 30 from the inner cylinder or tubular member 20. The portion of greater diameter 26 provides means for preventing the inner tubular member 20 from being pushed entirely within the confines of the outer cylindrical member 10. A coil spring 32 is positioned within the watch strap spring bar and biases the heads 28 and 16 of the studs 30 and 14, respectively. This, in turn, causes the inner tubular member 20 to be urged outwardly of the outer tubular member 10. Hence, when the studs 30 and 14 are positioned within suitable receiving apertures in the case of the wrist watch the spring 32 tends to continuously urge these members into their proper position.

Perhaps the most important element of the present invention resides in the split collars 34 which are positioned in friction engagement about the inner tubular member 20. The split collars 34 provide means for limiting the minimum size which the watch strap spring bar may attain, since the engagement of the split collar 34 with the inwardly turned edge 28 of the outer tubular member 10 would prevent any further decrease in size. Hence, by judicious positioning of the collars 34, such will render it impossible for any accidental disengagement of the watch strap spring bar from the watch case, thus per-

mitting the detachment of the strap from the wrist watch, causing a loss of or damage to the wrist watch. However, when it is intended to remove the watch strap, it is merely necessary to apply pressure on the outer end of the inner tubular member, thus permitting a reduction in size of the bar.

Referring now to the embodiment as shown in Figures 3 and 4, it will be seen that herein is provided a similar device which has an outer tubular member 50 crimped to provide a reduced sleeve end 52 for retaining the inner tubular or cylindrical member 54 in engagement with the outer tubular member 50, the inner tubular member 54 being provided with an end wall 56 of greater diameter. A spring 58 is provided for biasing the end walls 56 and the head 60 of a stud 62 having a recess 64 therein adapted to engage pins formed on the watch case. The inner cylindrical member 54 is provided with a recess 66 for engagement with the other of the pins. A split collar 68 similar to the split collar 34 is provided for precisely the same function as the collar 34 performs.

Referring now to Figures 5 and 6, the third form of the invention comprises a tubular member 70 which is crimped and internally threaded, to provide a reduced sleeve end 72 for threaded engagement with an inner exteriorly threaded tubular member 74. The outer tubular member 70 is provided with an end wall 76 having an aperture therethrough through which the stud 78 extends. The inner tubular member 74 is provided with an end wall portion 80 of greater diameter than the rest of the tubular member 74 through which stud 82 extends. A coil spring under compression and indicated by reference numeral 84 continuously biases the heads 86 and 88 of the studs 82 and 78, respectively. The threaded portions 72 and 74 determine the size of the watch strap spring bar.

Referring now to the embodiment of the invention as shown in Figures 7 and 8, it will be seen that the outer tubular member 90 has attached thereto and integrally formed therewith the stud 92 at one end. The other end of the tubular member 90 is provided with a crimped reduced sleeve end as at 94 to provide retaining means which will limit the position of the inner tubular member 96 which has an end wall 98 adapted to engage the crimped portion 94. A stud 100 is retained within the inner tubular member 96 by means of the crimped end wall 102 which is also provided with a peripheral portion 104 of greater diameter. This portion 104 retains the split collar 106 on the inner tubular member and prevents the loss thereof. The action of the portion 104 is identical with the action of the portion 26 of the embodiment shown in Figures 1 and 2. A spring 108 is provided for biasing the end wall 98 and the stud 100. The split collar 106, again the most important element of the invention, provides means for limiting the minimum size that this form of the invention can obtain.

In Figures 9 and 10 there is shown the last of the embodiments of the invention which include an outer tubular member 110 having a stud 112 integrally formed at one end thereof. The outer tubular member is threaded as at 114 for engagement with the threaded portions 116 or 118 formed in the inner tubular member 120 which has end walls 122 and 124. The end wall 124 is provided with a peripheral flange 126 and has an aperture therethrough in which stud 128 extends, the stud 128 being provided with a shoulder 130 for depressing such when it is desired to re-

move the device from engagement with the watch case. A coil spring 132 biases the head 134 of the stud 128 and the end wall 122. The crimped portion 114 in the outer tubular member and the recesses 116 in the inner tubular member 120 provide means for predetermining the size limitations of the watch strap spring bar.

Since, from the foregoing, the construction and advantages of each of these modifications of watch strap spring bars are readily apparent, further description is believed to be unnecessary.

However, since numerous modifications will readily occur to those skilled in the art after a consideration of the foregoing specification and accompanying drawings, it is not intended to limit the invention to the precise embodiment shown and described, but all suitable modifications and equivalents may be readily resorted to which fall within the scope of the appended claims.

Having described the invention, what is claimed as new is:

1. A watch strap spring bar connector comprising an outer tubular member, an inner tubular member slidably received in said outer tubular member, means on said inner tubular member for determining the operative size of said connector when in use, and means preventing separation of said inner tubular member from said outer tubular member, an end wall forming a part of said inner tubular member, a stud slidably carried by said inner tubular member, means preventing disengagement of said stud from said inner tubular member, and a compression spring biasing said end wall and said stud.

2. A watch strap spring bar connector comprising an outer tubular member, an inner tubular member slidably received in said outer tubular member and having a peripheral portion of relatively larger diameter, exposed means on said inner tubular member for determining the operative size of said connector when in use, and means preventing separation of said inner tubular member from said outer tubular member, an end wall forming a part of said inner tubular member, a stud slidably carried by said inner tubular member, means preventing disengagement of said stud from said inner tubular member, and a compression spring biasing said end wall and said stud, said first-recited means comprising a resilient collar settable along said inner tubular member in friction gripping engagement therewith to engage said peripheral portion and be engaged by the outer tubular member.
